UNITED STATES PATENT OFFICE

WILLIAM R. MOORE, JR., OF HAGERSTOWN, MARYLAND, ASSIGNOR TO DECA-DISC PHONOGRAPH COMPANY, OF WAYNESBORO, PENNSYLVANIA, A CORPORATION OF PENNSYLVANIA

AUTOMATIC TALKING MACHINE

Application filed February 16, 1927. Serial No. 168,674.

My invention relates to automatic phonographs and it is an object thereof to provide an improved mechanism of this character which shall be capable of playing a series of records continuously in a predetermined order and capable also of repeating the series indefinitely in the same order if desired.

A further object of the invention is to provide means whereby the machine will be automatically stopped after playing a given number of records predetermined by a manually operated selective control. For instance, if the indicator on the control is set at 5, the machine will play five records in succession and automatically stop at the completion of the fifth.

Another object of the invention is to provide means whereby a record, or a part of a record, can be skipped without stopping the operation of the machine and without interrupting the music, except for so long a time as is required for the record-changing mechanism to pass through a cycle of operations.

Still another object is to provide means whereby records of different sizes, e. g., either ten inch or twelve inch records may be played on the same machine.

Referring to the accompanying drawings which are made a part hereof and on which similar reference characters indicate similar parts,

Figure 1 is an elevation of the mechanism with parts broken away for clearer illustration,

Figure 2, a horizontal section on the line 2—2 of Figure 1,

Figure 3, a detail horizontal section of one of the switch elements,

Figure 4, a face view of the same,

Figure 5, a plan view of the manually operated selective controller,

Figure 6, an elevation thereof,

Figure 7, a side elevation of a circuit closing switch operated by the tone arm,

Figure 8, an end elevation thereof,

Figure 9, a detail of the operating lever therefor,

Figure 10, a diagrammatic plan view of the tone arm and record,

Figure 11, a vertical section through one of the record supporting members,

Figure 12, a diagram of the electric wiring,

Figure 13, an enlarged detail view of the friction drive gear for the cam shaft,

Figure 14, a view of a modified form of the record supporting members, and

Figure 15 is an enlarged detail of a ratchet and the spring which holds it in place,

Figure 16 is an enlarged detail view of the record changing and supporting means,

Figure 17 is an enlarged view showing a detail of the ratchet and pawl mechanism for supporting the record table, and

Figure 18, a section on line 18—18 of Figure 17.

The mechanism of my invention comprises a frame or spider 20 suitably secured beneath a board or table 21 forming a part of a cabinet of any suitable design. Beneath the spider 20 is secured a motor, preferably of the induction type having in this instance three field pieces 22, 23 and 24 and a disk armature 25 which drives the turntable 32 upon which is superimposed the record base 26 which carries the records when being played. The disk 25 is mounted on a tubular shaft 27 having a worm gear connection, as in co-pending application No. 53,190 of Bodwell and Bellows, filed August 28, 1925 for combined talking machine and advertising device, with a centrifugal speed governor 28 shown in Figure 1.

The shaft 27 carries an inwardly projecting pin 29 adapted to engage a vertical slot 30 in a tubular bottom 31 of turntable 32 which bears beneath the record base 26 and rotates the same through frictional contact. The slot 30 permits of free vertical movement of the tube 31 during the transfer of records by the action of a spring 32' in one direction and by the down pull of the record base 26 actuated by a spindle 33 which passes downwardly through the tube 31. Near its lower end the spindle 33 is provided with annular ratchet teeth 34 for engagement by a pawl 35 slidable transversely of the spindle and having teeth at the left hand side for engagement with the teeth 34. A spring

36 tends to move the pawl to the right into engagement with said teeth and a pin 37 on a cylindrical element 38 having a cam track for a pin for lifting the spindle 33 reaches 5 through a slot 39 in the frame surrounding the driving spindle to strike against the pawl 35 and move it out of engagement with said teeth, this taking place at a time when the spindle 33 and the record base have been 10 lifted to their highest position. The spindle 33 has an annular collar 40 adjacent its lower end against which rests a spring 41 which has for its main purpose to lift the record base and the records thereon up 15 against the fingers 92 hereinafter described and to move the base upward upon release of the pawl 35 by the pin 37, such movement being reduced at each addition of a record while the base is taking on records by a distance 20 sufficient to compensate for the thickness of the additional record which has just been added to the record base and bring the playing surface of the topmost record on the base of the same height with reference 25 to the needle, which remains always at the same horizontal elevation. Another function of the spring is to lift the record base with all of the records thereon during the restoring operation to the proper height for 30 restoring the records to a position from which they may again be selected and placed one by one on the record base as hereinafter described.

A vertical shaft 42 is journalled in a bearing formed in the underside of one of the arms of the spider 20 and another bearing in a bracket 43 depending from said spider and has secured thereon adjacent its lower end, the cylindrical cam 38. The shaft 42 is rotated by means of a motor 43' having a worm 44 engaging with a worm wheel 45 loosely mounted on the shaft 42. A pinion 46 is formed integral with the upper end of the hub portion 47 of said wheel 45 and drives one 45 of a pair of twin gears 48 and 49 which are loosely mounted on an idle spindle 50 secured to the frame. In order to provide a safety device to eliminate the possibility of stripping the teeth of gear 45 should any unforeseen mishap occur, I mount the gear 48 on the shaft 50 in frictional engagement with two friction collars 48' and 49' held in engagement therewith by means of the ring nut 50' as shown in Fig. 13. The gear 49 meshes 55 with a larger gear 51 secured to the shaft 42. It will be readily understood that this train of gears will impart a steady and powerful rotation of the shaft 42 and its associated cams. The cam 38 has also mounted thereon 60 two circumferential switch-operating elements 52 and 53 constructed of heavy wire and secured thereto by passing the ends of the wires through openings in the cam body.

Shaft 42 also carries means for operating 65 the mechanism for swinging the tone-arm 54

out of engagement with the record during the replacing of the last played record with another and for returning the tone arm to playing position.

Heretofore, machines of this character were limited to one size of record, i. e., either 78 10 inch or 12 inch, whereas my improved machine is capable of playing both 10 inch or 12 inch records, the change being made by simply moving a small lever, conveniently 75 located, from one position to the other as will be explained.

Secured to the upper end of the shaft 42 is a cam 55 which controls the movement 80 of the tone arm 54. In Fig. 1 the cam is shown in the position assumed during the playing of a record, while in Fig. 2 it is in the position where the tone arm is moved out of the path of movement of the records. As shown in Fig. 1, the mechanism is in the 85 position to play a 12 inch record. The cam 55 is provided with a low surface 56, a quick rising surface 57 and a circumferential high surface 58. At its extreme end the high surface 58 is divided into two portions 59 90 and 60, of which the portion 59 extends further out radially of the shaft than does the portion 60, the latter portion being below portion 59 in a vertical sense, said portions 95 of the cam surface providing independent tracks for a purpose to be explained later.

The tone arm 54 has a vertical tubular portion 60' which extends through the table 21 and has secured thereto an arm 61 provided with a central elongated slot 62 running practically from end to end. The free end of the arm is bent to form a bracket 63 in which is secured an adjustable screw 64 to be herein-after more fully explained. Depending from the frame 20 is a fixed headed pin 65 100 upon which is slidably mounted a grooved sleeve 66 having secured to its upper surface an arm 67 which is slotted at 68 to receive a depending pin 69 adjustably secured in the slot 62 of the arm 61. At a point on the arm 67 adjacent to and extending towards the cam 55 is a pointed finger 70 adapted at predetermined times to coact with the various cam surfaces to move the tone arm. The finger 70 together with the arms 61 and 67 105 are normally forced in the direction of the cam by means of a light tension spring 71 secured at one end to the finger 70 and at its opposite end to the bracket 63. A rectangular block 72 is secured to the upper side of the arm 67 and engages the end of a screw 73 carried by a bell-crank lever 74 which is fulcrumed on a pin 75 depending from the frame 20. The screw 73 is held in engagement with the block 72 by means of a spring 76 secured 110 to the opposite arm of the bell-crank lever 74 and to a pin in the frame 20 thereby preventing the arm 67 from swinging too far and also assisting in holding the finger 70 115 in contact with the cam surfaces, the tension 120

exerted through the lever being greater than that of spring 71.

The cam 55 has two tracks 59 and 60 for the finger 70 to travel on, the upper track being followed when 12 inch records are being used and the lower track being followed when 10 inch records are being used. The change from one position to the other, as occasioned by the size of the record, is accomplished in the following manner.

The sleeve 66 as before mentioned is adapted to slide vertically on the pin 65 and carries with it the arm 67. In order to change the position of the sleeve 66 and arm 67, I provide a forked lever 77 pivoted in a depending lug 78 and having pins 79 in its forked portion engaging the groove in the sleeve 66. The free end of the lever 77 is pivotally mounted in a vertical plunger 80 slidable in a housing 81 secured to the table 21. A bell-crank lever 81' is pivoted in arms 82 formed integral with the housing and has one arm 83 pivoted in the plunger 80 and its other arm extending upward through a slot in the table 21 and provided with a knob by which the lever 81' is manually operated. It will be readily understood from Fig. 1 of the drawings that movement of the lever 81' to the left will rock the lever 77 through its connection with the plunger 80 causing the sleeve 66 and arm 67 to assume their lower position which will at the proper time cause the finger 70 to engage the cam surface or track 60 for a purpose to be more fully explained. In order to relieve the tension on the lever 74 when the device is set for playing 10 inch records, I provide a post 84 pivotally connected to the lever 77 said post having a large lower end 85 which engages the short arm of the lever 74 when the device is in a position to play 12 inch records, and at a higher point a smaller end 86 which is brought into engagement with the short arm of the lever 74 when 10 inch records are being played.

The record base may carry one or more records, the uppermost one being in playing relation with the tone arm. As the machine is intended to utilize a plurality of records in succession, it becomes necessary to provide means for supporting the records of the series that have been played. Such means, more fully illustrated and explained in application 53,190 above referred to, comprises a plurality of posts 90 which are hollow and open at their inner side. Each post contains a pivoted support 91 U-shaped in section and carrying at its upper end a pointed finger 92 for separating selected records and limiting the upward movement of the record base. A leaf spring is provided at 93 said spring acting on the flat rear end of the finger 92 to hold it normally in the position shown but with freedom to move angularly to a slight extent during the record-separating

action. Another support 94, also U-shaped in section, is pivotally mounted at 95, said support comprising two sides separated to a slight extent.

A lever 96 is located between the sides of the U-shaped support 94, said lever being supplied at its upper end with an inwardly-directed projection 97. At its lower end the lever has a tail 98 with a lug 99 extending downward therefrom and pressed against a stop 107 by a spring 100 which limits inward movement of lever 96. A catch 101 has a hook portion extending through an opening in the support 94 for engagement with a cross piece 102 and the catch has a lug 103 at its lower side adjacent to the upper side of the tail 98. A pin 104 limits the inward movement of the support 94. The supports 91 and 94 have upper and lower arms but for convenience their movements are referred to as "outward" and "inward", reference being had for this purpose to the upper arms only while the lower arms are ignored.

A cam lever 105 is pivoted on the support 91 between the sides thereof and is pressed upward and backward by a spring 10 coiled in a flat spiral. The cam face of the lever bears against the lower end of the lug 99 to hold the lever 96 at the most elevated position permitted by the pin and slot connection at 95. The pin 107 on post 90 also limits the movement of cam lever 105 in one direction and said pin also serves to force cam 105 at times into inoperative position. A stop 108 is fixed to the support 91 and bears at its forward end against a depressed part of the outer face of the lever 96, which holds top of same back against support 94 when the finger 92 is out. A spring 109 is fixed at one end to the U-shaped support 91 between the sides thereof and is bent upward at its free end to engage against the rear face of the support 94. A pin 110 limits the inward movement of the upper end of support 94.

In Fig. 14, I illustrated a modified form of record supporting post which is similar in action to the one just described, but which contains fewer parts and is much less intricate. It comprises a hollow post 90' open at its inner side and containing a pivoted support 91' U-shaped in section and carrying at its upper end a pointed spring finger 92' for separating selected records and limiting the upward movement of the record base. The finger comprises a compound bend 93' which holds it normally in the position shown but with freedom to move slightly during the record-separating action. Another support 94', also U-shaped in section, is pivotally mounted at 95', said support comprising two sides separated to a slight extent.

A lever 96' is located between the sides of the U-shaped support 94', said lever being supplied at its upper end with an inwardly-

directed projection 97'. At the extreme lower end the lever 96' is provided with a pin 99' over which passes a perforation in a spring 106' which spring tends to force the lever upward as shown. A catch 101' has a hook portion extending through an opening in the support 94' for engagement with a cross piece 102' on the support 94' and has an arm 103' extending from its under side with its end resting on a shoulder 105' formed on the lever 96' so that when the lever 96' is depressed by virtue of records thereon, the hook portion of the catch 101' will engage the cross piece 102' and cause the support 91' to swing. A stop 108' is fixed to the support 91' and limits the upward movement of the catch 101'. A spring 109' is fixed at one end to the U-shaped support 91' between the sides thereof and is bent upward at its free end to engage against the rear face of the support 94'. A pin 110' limits the inward movement of the upper end of the support 94'.

Fig. 10 of the drawings discloses a diagrammatic plan view of the tone arm and reproducer in position on the record, also the playing groove 111 and rapid advance groove 112 of the record. During the playing operation, the reproducer and tone arm advance 25 in the direction of the arrow in Fig. 10 very slowly. When the end of the selection has been reached, the needle swings the tone arm and the arm 61 inward causing the screw 64 to engage a bevel portion 113 of a tripper 30 arm 114 (Figs. 2, 7, and 8) of an electric switch or contact device 115. This switch comprises two contact members 116 and 117 which are out of contact during the playing of a record and which are in series with 35 the motor 43' which operates the cam 38. The tripper arm 114 is fulcrumed at 118 in the body of the switch and is provided adjacent the fulcrum with a notch at 119 designed to support in elevated position a pivoted arm 40 120 which extends to a point directly above and adjacent the contact 117 for the purpose of closing the switch, to be hereinafter more fully explained. The opposite end of the arm 120 is pressed upwards by means of a 45 spring 121 located in an opening in the switch body and has in its extreme end an adjustable screw 122 adapted to be acted upon by an arm 123 secured to one of the pivoted supports 91 to reset the switch. The arm 114 is 50 normally retained in the elevated position shown in Fig. 7, by means of a wire spring 124 clearly disclosed in Fig. 9.

Located on the depending bracket 43 adjacent the cam 38 is an insulating base 125 upon which are mounted switches 126 and 127. The switch 126 comprises a stationary contact member 128 and a spring member 129. Said spring member is provided on its free end with an actuating block 130 of insulating material designed to coact with the

cam element 53 to open and close the contacts. The switch 127 comprises an angularly disposed stationary member 131 and a spring member 132 which is likewise provided on its free end with an actuating block 133 of insulating material designed to coact with the cam element 52, all to be hereinafter more fully explained.

It can be seen from the diagram, Fig. 12, that a main line control switch 134 is placed in the circuit of both motors, so that after the records are placed on the machine and the switch closed, the machine will play continuously. This may at times be objectionable and in order to have the apparatus play a predetermined number of records and stop, I provide a selector control switch 135 in the circuit of the turntable motor as follows: A knob (Fig. 6) 136 is provided on a shaft protruding downward through the table 21 and having a pointer 137 over a dial on the board. Said shaft is fastened permanently to a ratchet wheel 138 which in turn is controlled by a coiled spring 139. An escapement pawl 140 pivoted as shown controls the return movement of the ratchet wheel. Contact elements 141 and 142, normally in contact, extend over the ratchet wheel and the element 141 projects within the path of movement of a pin 143 fixed to the wheel 138. The escapement pawl 140 is provided with an extension 144 which lies in the path of movement of an adjustable screw 145 (Figs. 2 and 5) secured in the end of an arm 146 depending from one of the pivoted supports 91 with the result that at the time of changing records, the arm 146 will trip the pawl 140 allowing the wheel 138 to revolve one notch in a clockwise direction. This action will continue in a step-by-step manner until the pin 143 on the wheel 138 strikes the protruding end of the element 141 and breaks the circuit to the motor. The escapement wheel may be provided with any number of teeth desired as only one record can be played for each tooth released by the operator when he turns the knob 136. For instance, should the knob be turned counter-clockwise five notches, five records will be played in succession and the machine will stop.

The diagram (Fig. 12) discloses the main line circuit wire 150 connected by a wire 151 through the switch 134 to the coils 22, 23 and 24 then by the wire 152 through the contact 141 to contact 142, and then through wire 153 back to the main line wire 154. This circuit drives the turntable motor continuously as long as the contacts 141 and 142 are closed. The circuit for the motor 43' comprises a wire 155 tapped into wire 151 and connected to one side of the motor. From the other side of the motor a wire 156 is connected to the contact 129 then through wire 157 to contact 116. Another wire 158 is tapped into wire 153 and connects to contact 128 then by the

wire 159 to the contact 117. It is to be understood that while a record is playing, the switch 135 comprising contacts 141 and 142 is closed supplying current to the turntable motor, while the switches 126 and 127 and 5 also the contacts 116 and 117 are open.

The operation of the device is as follows:

The records, say ten in number are placed one on the record base and nine on the supports 94 of the posts 90 and the knob 136 is turned ten notches permitting the contacts 141 and 142 to close the circuit at this point, then the closing of the switch 134 applies current to the turntable motor. The tone arm 15 moves towards the center of the record as the record is played and is finally carried in quickly by the rapid advance groove 112 which closes the contacts 116 and 117 causing motor 43' to start, which 20 through the connecting mechanism, revolves the cam 38 causing the turntable and record base to be lowered and at the same time causes cam 55 to move the tone arm away from the records and starts the record base to rise to 25 change the record. The outward movement of the tone arm breaks the contact at 116 and 117, and the raising of the record base causes the supports 91 to tilt thereby forcing the arm 123 down on the screw 122 on the lever 30 120 and resetting the switch 115 in open position, but before this switch is opened the switch operating element 53 has passed from beneath the block 130 and closed the contact between switch 128 and spring 129 hereby 35 maintaining the circuit for the motor 43' until the record-change is completed. At the same time the arm 146 on another support 91 makes contact with the pawl mechanism of the escapement (Fig. 5) allowing the ratchet 40 to advance clockwise one notch and leaving the contacts 141, 142 closed.

The continued operation of the motor 43 causes the transfer of another record to the record base which again moves to a level below the playing level allowing the cam 55 to move the tone arm into the playing position and again raise the record base and record into contact with the needle in the reproducer. During this operation the turntable motor 50 has been constantly revolving, but I have found that the additional friction caused by the initial contact of the needle with the record causes a slight diminution in the speed of the record, therefore to overcome this objection, I find it necessary to boost the current in the motor by momentarily bridging one of the field coils out of circuit. This I accomplish by providing a wire 161 leading from the outlet side of the coil 24 to a contact 131. These contacts are normally open but just before the needle is applied to the record, the switch-operating cam wire 55 raises the block 133 closing the circuit through switch members 131 and 132 momentarily 60 and allowing all of the current to pass

through the coils 22 and 24 which produces an additional torque in the turntable motor sufficient to overcome the friction of the needle. The switch 127 is then opened and the next record is played. This sequence of operations will continue until the pin 143 finally 70 opens the circuit in the control switch and so stops the turntable motor.

It may be that one of the series of records does not meet with the favor of the audience 75 In such case it may be omitted either wholly or in part by depressing a shaft 162 (Fig. 7) projecting up through a boss on table 21, said shaft having a bent arm 163 resting on tripper arm 114. This depresses the tripper arm 80 and releases arm 120 closing the circuit at 116, 117 to start the record-changing mechanism which will then bring the next record into operation as above explained.

In case continuous operation is desired the selector control switch 135 (Fig. 5) may be rendered inoperative by means of a switch 164 in a branch circuit (Fig. 12) bridging the 85 switch 135.

By the use of the induction motor, as above 90 described, it will be understood that the movement of the record base can be arrested temporarily without any need to cut off the current to the motor, and without any danger of injury to the motor through failure to cut off the current as aforesaid. Users of a talking machine frequently interrupt the operation of the machine by grasping the turntable and holding it against the action of the motor. This would tend to burn out a part of 95 the wiring in a machine driven by an electric motor of a different type but with an induction motor no damage can result. The use of the induction motor is also advantageous in that it affords a very smooth and uniform drive for the record while the provision of a separate motor for the record-changing mechanism permits me to employ a motor of relatively great torque for actuating said mechanism, which last named motor would be less suitable for driving the turntable because of the necessity of a reducing train of gearing and a less even and uniform drive for the turntable.

It will be obvious to those skilled in the 100 art that various changes may be made in my device, without departing from the spirit of my invention, and I, therefore, do not limit myself to what is shown in the drawings and described in the specification, but only 105 as set forth in the appended claims.

Having thus fully described my said invention, what I claim as new and desire to secure by Letters Patent, is:

1. The combination of a rotating record 110 base, an induction motor for driving the same, means for supporting a stack of records, automatic means for shifting records from the base to the stack and vice versa whereby the talking machine may be operated continu- 115

ously, and means including an escapement for selectively predetermining the number of records to be played, substantially as set forth.

2. The combination of a rotating record base, an induction motor for driving the same, means for supporting a stack of records, automatic means for shifting records from the base to the stack and vice versa whereby the talking machine may be operated continuously, means including an escapement for selectively predetermining the number of records to be played, and means for putting said predetermining means out of action thereby causing the operation to be continuous, substantially as set forth.

3. The combination of a rotating record base, an induction motor for driving the same, means for supporting a stack of records, automatic means for shifting records from the base to the stack and vice versa whereby the talking machine may be operated continuously, means including an escapement for selectively predetermining the number of records to be played, and means in connection with the record-shifting means for actuating the escapement at each change of records, substantially as set forth.

4. The combination of a rotating record base, an induction motor for driving the same, means for supporting a stack of records, automatic means for shifting records from the base to the stack and vice versa whereby the talking machine may be operated continuously, means including an escapement for selectively predetermining the number of records to be played, means in connection with the record-shifting means for actuating the escapement at each change of records, and a switch in circuit with said induction motor operable by said escapement at the zero point, substantially as set forth.

5. The combination of a rotating record base, an induction motor for driving the same, means for supporting a stack of records, automatic means for shifting records from the base to the stack and vice versa whereby the talking machine may be operated continuously, means including an escapement for selectively predetermining the number of records to be played, means in connection with the record-shifting means for actuating the escapement at each change of records, a switch in circuit with said induction motor operable by said escapement at the zero point and another switch in a branch of the motor circuit bridging said first-named switch, substantially as set forth.

6. In combination with a talking machine having a rotating record base and a tone arm, means for supporting a stack of records, record-changing means, means for moving the tone arm out of the way during a record-changing operation and in to various distances according to the size of the record comprising a cam with tracks differentiated ac-

cording to the size of the records, connections from the cam to the tone arm including a cam follower, and means whereby the cam follower may be shifted from one track to the other, substantially as set forth.

7. In combination with a talking machine having a rotating record base and a tone arm, means for supporting a stack of records, record-changing means, means for moving the tone arm out of the way during a record-changing operation and in to various distances according to the size of the record comprising a cam with tracks differentiated according to the size of the records, connections from the cam to the tone arm including a cam follower, means whereby the cam follower may be shifted from one track to the other, and means acting resiliently to hold the cam follower against said cam, substantially as set forth.

8. In combination with a talking machine having a rotating record base and a tone arm, means for supporting a stack of records, record-changing means, means for moving the tone arm out of the way during a record-changing operation and in to various distances according to the size of the record comprising a cam with tracks differentiated according to the size of the records, connections from the cam to the tone arm including a cam follower, means whereby the cam follower may be shifted from one track to the other, means acting resiliently to hold the cam follower against said cam, and means whereby the tension of said resilient means may be varied according to the size of the record, substantially as set forth.

9. In combination with a talking machine having a rotating record base and a tone arm, means for supporting a stack of records, record-changing means, means for moving the tone arm out of the way during a record-changing operation and in to various distances according to the size of the record comprising a cam with tracks differentiated according to the size of the records, connections from the cam to the tone arm including a cam follower, means whereby the cam follower may be shifted from one track to the other, means acting resiliently to hold the cam follower against said cam, and means whereby the tension of such resilient means is adjusted automatically in changing the follower from one track to the other to accommodate it to the size of the record, substantially as set forth.

10. The combination of a talking machine having a rotating record base, means for supporting a stack of records above said base, automatic means for shifting records from the record base to the stack and vice versa and manually operable means whereby the record-changing means may be set in operation during the playing of a record, substantially as set forth.

11. The combination of a talking machine having a rotating record base and a tone arm, a motor for driving the record base, means for supporting a set of inactive records, means for shifting a record from the record base to the inactive set including a rotary cylindrical element having a cam track, a motor for driving said shifting means, means operated by the tone arm for closing the circuit of the last-named motor, a switch operated to break said circuit in the operation of said record-shifting means, a switch in a branch circuit bridging said first-named switch, and a cam on said cylindrical element for closing said last-named switch before the first switch is closed, said cam maintaining its switch closed until the record-shifting operation is completed, substantially as set forth. 70
12. In a talking machine, a tone arm, a rotating record base combined with means for supporting and driving the same including an induction motor, record-changing means, means for removing the tone arm prior to record-change and replacing it on the new record, and means for imparting additional torque to the turntable as the needle of the tone arm impinges on the record, substantially as set forth. 80
13. In a talking machine, a rotating record base, a tone arm, an induction motor for driving the record base, record-changing means including means for removing the tone arm from playing position and returning it thereto, and means for boosting the current in the motor as the needle of the tone arm impinges on the new record, substantially as set forth. 85
14. In a talking machine, a tone arm, a rotating record base, an induction motor driving the record base, said motor having a plurality of field coils, record-changing means including means for removing the tone arm and returning it to playing position on the new record, and means for bridging a field coil as the needle of the tone arm impinges on the new record, substantially as set forth. 90
15. In a talking machine, a tone arm, a rotating record base, an induction motor driving the record base, said motor having a plurality of field coils, record-changing means including means for removing the tone arm and returning it to playing position on the new record, a rotary cylindrical element in said record-changing means having a cam track for lifting the record base, a branch circuit bridging one of said field coils, a switch in said bridge circuit and a cam on said cylindrical element for closing said last-named switch to bridge the coil momentarily as the needle of the tone arm impinges on the record, substantially as set forth. 95
16. In a talking machine, a rotating record base, a continuously driven motor for operating the same, a tone arm, record- 100
- changing means including a rotary cam, a motor for operating the record-changing means and for moving the tone arm into and out of operative position, a switch in the circuit of the last-named motor, said switch being closed by the tone arm in its innermost position to start the motor and being opened by the record-changing means, a switch in a branch circuit bridging the first-named switch and means on said cam for controlling the last-named switch, substantially as set forth. 105
17. In a talking machine, a rotating record base, a continuously driven induction motor with a plurality of field coils, a tone arm, record-changing means including a rotary cam, a motor for operating the record-changing means and for moving the tone arm into and out of operative position, a switch in the circuit of the last-named motor, said switch being closed by the tone arm in its innermost position to start the motor and being opened by the record-changing means, a switch in a branch circuit bridging the first-named switch, a branch circuit bridging one of said field coils, and means on said cam for controlling the switches of both of said bridging circuits, substantially as set forth. 110
18. In combination with a talking machine having a rotating record base and a tone arm, means for supporting a stack of records, record-changing means, means for moving the tone arm out of the way during a record-changing operation and in to various distances according to the size of the record, resilient means tending to return the tone arm to playing position, and means for varying the action of said resilient means to a predetermined extent according to the size of the record, substantially as set forth. 115
- In witness whereof, I have hereunto set my hand at Waynesboro, Pennsylvania this 15th day of February, A. D. nineteen hundred and twenty-seven. 120
